CONTACT COPYING MACHINE

Geza Szasz, New York, N. Y.

Application April 4, 1939, Serial No. 265,916

7 Claims. (Cl. 95—77.5)

This invention relates to photo-copying machines and deals more particularly with devices of this character wherein a high intensity light source is employed.

5 In one form of prior construction there was employed a light source emitting long wave length light such as produced by an ordinary 100 watt light bulb. This source of light being of relatively low intensity could be employed when 10 haloid silver emulsions on the photographic paper were used. The devices were usually box-like in structure and employed a flat copying surface.

Another type of prior device used a light source 15 emitting rays of short wave length and was particularly adapted for the making of blue prints. This type of lighting was either in the form of carbon arc lamps or low pressure mercury vapor lamps used in connection with a paper feed 20 mechanism whereby the paper moved in relation to said lamp.

The present invention seeks to provide a contact photo-copying machine on which may be used either haloid silver photographic paper, 25 blue print paper or other light sensitive dye coated material.

The invention seeks to provide a light source emitting short wave length rays and combining said light source with a preferably hemi-cylindrical transparent platen which permits the transmission of short wave length rays of light and upon which the negative and the sensitized paper may be arranged for exposure of the light of said source.

35 The invention further contemplates the provision of shutter means either alone or combined with a filter.

Another feature of the invention resides in the provision of time controlled electrical means 40 for operating the above-mentioned shutter means for obtaining the desired length of exposure.

It is also contemplated to incorporate in the electrical system of the machine a reactor means in the light source circuit so that the machine 45 may be interchangeably used for the exposure of various types of light sensitive materials.

Another object of the invention resides in the provision of means for cooling the light source in view of its high intensity.

50 In order to determine the light transmitting qualities of any negative to be copied on the machine, there is also contemplated the provision of light sensitive means for application to the light transmitted by a negative whereby exposure time thereof may be determined.

Accordingly, the invention consists in the features of construction, combination of elements and arrangements of parts, all as will be illustratively set forth in the following description, and the scope of the application of which will be indicated in the appended claims.

With these and other objects in view there has been illustrated on the accompanying drawings one form in which the invention may be conveniently embodied in practice.

10

In the drawings:

Fig. 1 is a side elevational view partly in cross-section, of a machine incorporating features of the invention;

Fig. 2 is a transverse cross-sectional view 15 thereof;

Fig. 3 is a diagrammatic view showing the electrical arrangements of the machine;

Fig. 4 is a partial elevational view, partial sectional view, of one end of a modified form of 20 light source, shielding means therefor, and associated shutter means;

Fig. 5 is a cross-sectional view thereof;

Fig. 6 is a side elevational view of one end of 25 the machine illustrating the use of the light sensitive means for determining the exposure time.

In that embodiment of the invention here illustrated, the copying machine preferably comprises a base housing 10 formed with spaced upright portions 11 at each end of the machine. 30 These upright portions are preferably provided with a curved surface 12 forming a seat for a transparent hemi-cylindrical platen 13 bridging the gap between the seats of the wall 11. In order to obviate direct contact between the 35 platen 13 and the metal of the uprights 11 there may be interposed cushioning pads such as shown at 14 between said platen and the seats.

In the above manner there is provided an 40 enclosed chamber 15 near the lower portion of which is arranged a tubular light source 16 extending longitudinally of the machine and comprising a quartz or short wave transmitting glass housing with a suitable inert gas therein.

Surrounding said light source 16 there is arranged shutter means comprising the stationary half shell 17 and the rotatable half shell 18. Extending from each lateral portion of the stationary shell 17 towards the front and rear of the machine there is preferably arranged a reflector member 19 comprising a sheet having a highly reflecting surface. The rotatable shell 18 is also provided on its inner surface with a high reflection polish.

When exposure is not had, the rotatable shell 55

18 is arranged in a position to overstand the light source 16 and together with the shell 17 to effectively cover and conceal said light source.

When exposure is desired the rotatable shell 5 is arranged as shown in Fig. 2 exposing the platen to the light rays from said source 16 and to the reflected rays from the highly reflecting inner surface of said rotatable shell and of the mentioned plates 19.

10 The means for operating the mentioned shutter means in the present instance is electrical and comprises a solenoid 20 having a coil 21 and a floating core 22. The core is connected, as shown, to a link 23 having connection with a

15 two-armed lever 24 pivotally mounted on one of the uprights 11 at 25. The mentioned link 23 is preferably connected to the shorter arm 26 of the lever 24 and the free end of the longer arm 27 thereof serves to carry a preferably concavely curved gear rack 28. The latter is engaged with a gear 29 carried by the rotatable shell 18. A spring, such as shown at 30, may be employed in counter-acting relation to the force of the pull of the solenoid on its core.

25 It is evident from the foregoing that when exposure of the light source is desired the solenoid is energized against the force of the spring 30 to cause rotation of the shell 18 so it is disposed coincidently with the shell 17 and when 30 the solenoid is de-energized the spring 30 takes effect to restore the shell 18 to its light concealing position where it is arranged diametrically to the fixed shell 17.

The light source 16 is preferably operated 35 through the induced current supplied to a transformer 31 connected to an A. C. line as shown in Fig. 3. One side 32 of this line is connected as by means of a master switch 33 to the primary winding 34 of the transformer 31. The other side 35 of said line is connected to said winding. Thus the switch 33 controls the flow of current to the primary of the transformer.

The secondary winding 36 of the transformer 31 is connected in series with the light source 16 by conductors 37 and 38 and a switch 39 disposed to open or close the conductor 38. The above circuit is employed when the full intensity of the light source 16 is desired. When lower intensity is needed, a reactor 40 may be cut into 50 the secondary circuit by means of the switch 39 and it is this condition which is illustrated in Fig. 3.

One end of the coil 21 of the solenoid 20 is connected by means of a conductor 41 to the line 55 at 32 and the other end of said coil is connected to a switch 42 controlled by a time mechanism 43, the switch 42 being arranged in series in the line of the conductor 44 which is connected to the side 35 of the line. It is evident from the 60 foregoing that the solenoid 20 is controlled in its operation only by the time switch 42 and will operate when said time switch is operated.

The means for cooling the light source preferably comprises a motor 45 having a fan 46 arranged to blow a current of air along said light source for conducting heat away therefrom.

The motor 45 is connected by means of the conductor 47, to the conductor 44, and thus to one side 35 of the line, another conductor 48 being 70 connected to the switch 33 and thus to the other side 32 of the line. A switch 49 may be employed to cut the motor 45 into circuit even when the switch 33 is open, so that cooling of the light source may be had at any time.

75 As shown in Fig. 6 in physical form and at

the right of Fig. 3, electrically, the light sensitive means such as a photo cell 50 suitably housed may be connected by means of conductors 51 to a proper form of registering meter 52. Thus, when the light transmitting properties of a negative 5 are to be determined, the light sensitive cell 50 may be positioned against the negative as shown in Fig. 6 and reading of said property may be had on the scale of the meter 52. The latter may be arranged with dual scales selectively 10 readable under the mentioned selective conditions—one where the reactor 40 is used and the other, where the reactor 40 is cut out as by means of the switch 39.

Where the light source 16 is enclosed in quartz, 15 shielding thereof from the stream of air from the cooling fan 46, is unnecessary.

However, when glass, having short wave ray transmitting properties is used, it is desirable to shield the light source 16 as by means of a glass 20 tube 53, the latter being in the air stream series to conduct heat away from the light source.

The movable shutter shell 18 may be combined, for instance as shown in Figs. 4 and 5, with a light filter portion 18a oscillatable and arranged with said shutter shell to overstand the light source 16 when the shutter is open. This filter, preferably, has the property of filtering certain of the rays of light emanating from said light source and may be removably mounted to 30 render the device more flexibly variable in use.

In other respects the structure may be as before described, it being apparent that although the shutter mechanism here disclosed is preferred, other suitable shutter means may be employed.

It will be noted from the drawings that the light source 16 is positioned eccentrically in relation to the reflecting surface of the shutter shell 18 and preferably above the center of rotation thereof. Thus, a reflective uniform diffusion of light rays from said surface is obtained. This results in a uniform exposure of the negative and print paper.

In operation a negative 55 is placed on the 45 outer surface of the platen 13, the sensitized paper 56 is positioned thereover, and a covering shield 57 preferably of flexible fabric is then positioned over the paper. Said shield is resiliently mounted as at 58 to the rear of the 50 machine and catch or clip means 59 at the front of the machine is employed for holding the shield in place. The spring means 58 serves to impart a tension on the shield so that the negative and the photographic paper are in a flat condition 55 and in intimate contact with each other. The light transmitting properties of the negative and the exposure time of the photographic paper having been previously determined, and the switches 39 having been set, the timer 43 is set 60 to give the proper exposure time-controlled. The machine need not be watched since the time switch opens the solenoid circuit so that the spring 30 may act to enclose the light source at any time thereafter. The exposed photographic paper 56 may then be removed for subsequent treatment. The light source 16 remains on and is ready for another exposure upon operation of the shutter mechanism. The time switch having no control over the light circuit, consecutive 70 copying operations may be had until the master switch 33 is opened.

By the various means heretofore described, a wide range of variation or modification of characteristics may be had.

From the above description it will be apparent that there is thus provided a device of the character described which comprises a light source emitting short wave length rays, a hemi-cylindrical platen positioned in fixed relation to said source and adapted to receive a negative thereon, semi-cylindrical shutter means for said source comprising a stationary half portion and a swingable half portion complementary to said stationary portion, an electric circuit including a solenoid, time-controlled switch means for controlling operation of said solenoid, said swingable half portion having a reflecting inner surface, reflecting members at either side of said source, and means including gearing oscillatably operable by said solenoid and in engagement with said swingable portion for swinging the latter into open and closed positions, respectively, said swingable portion when swung in closed position surrounding with said stationary portion said light source, said swingable portion when swung in open position substantially overlying said stationary portion and permitting by its inner surface and in conjunction with said reflecting members transmission of said rays from said light source through said platen and said negative when located on the latter. The device possesses the particular features of advantages before enumerated as desirable, but which obviously is susceptible of modification and its form, proportions, detail construction and arrangement of parts without departing from the principle involved or sacrificing any of its advantages.

While there has been shown and described and pointed out the fundamental novel features of the invention as applied to preferred embodiments, it will be understood that various omissions and substitutions and changes in the form and details of the device illustrated and its operation may be made by those skilled in the art without departing from the spirit of the invention.

Having thus described the invention, what is claimed as new and desired to secure by Letters

Patent is:

1. In a copying machine of the character described the combination of a light source, shutter means adapted to enclose said source, an electric circuit, electro-magnetic means in said circuit, a transparent platen fixedly positioned above said source and adapted to receive a negative thereon, and means in said circuit for controlling said electro-magnetic means, said shutter means comprising a stationary member and a swingable member having a curved and highly reflecting inner surface, said swingable member being in driving connection with said electro-magnetic means and being oscillatable thereby to cover said light source when swung in a position thereabove forming with said stationary member a substantially closed housing for said source, and to expose said source when swung in a position below said source and substantially above said stationary member thereby forming with said inner surface a reflector for said light source for transmission of rays therefrom through said platen and said negative when placed thereon.

2. In a copying machine of the character described the combination of a short wave length light source, shutter means adapted to enclose said source, an electric circuit, electro-magnetic means in said circuit, a hemi-cylindrical transparent platen fixedly positioned above said source and adapted to receive a negative thereon, and time-controlled switch means in said circuit for

controlling said electro-magnetic means, said shutter means comprising complementary members, a stationary member and a swingable member, respectively, said swingable member having a curved and highly reflecting inner surface, said swingable member being in driving connection with said electro-magnetic means and being oscillatable thereby to cover said light source when swung in a position thereabove forming with said stationary member a substantially closed housing for said source, and to expose said source when swung in a position below said source and substantially above said stationary member thereby forming with said inner surface a reflector for said light source for transmission of rays therefrom through said platen and said negative when placed thereon.

3. In a copying machine of the character described a light source emitting short wave length rays, a hemi-cylindrical platen positioned in fixed relation to said source and adapted to receive a negative thereon, semi-cylindrical shutter means for said source comprising a stationary half portion and a swingable half portion complementary to said stationary portion, an electric circuit including a solenoid, time-controlled switch means for controlling operation of said solenoid, and means including gearing oscillatably operable by said solenoid and in engagement with said swingable portion for swinging the latter into open and closed positions, respectively, said swingable portion when swung in closed position surrounding with said stationary portion said light source, said swingable portion when swung in open position substantially overlying said stationary portion and being positioned relatively to said light source so as to permit rays emitted therefrom for transmission through said platen and said negative when located on the latter.

4. In a copying machine of the character described the combination of a short wave length light source, semi-cylindrical shutter means eccentrically arranged with respect to said source, an electric circuit, electro-magnetic means in said circuit, a hemi-cylindrical transparent platen fixedly positioned above said source and adapted to receive a negative thereon, time-controlled switch means in said circuit for controlling said electro-magnetic means, said shutter means comprising complementary members, a stationary member and a swingable member, respectively, a filter element associated with said swingable member and oscillatable therewith, said swingable member being in driving connection with said electro-magnetic means and being oscillatable thereby to conceal said light source when swung in a position thereabove forming with said stationary member a substantially closed housing for said source, and to expose said source when swung in a position below said source and substantially above said stationary member for transmission of rays from said source through said filter element to said platen.

5. In a copying machine of the character described a light source emitting short wave length rays, a hemi-cylindrical platen positioned in fixed relation to said source and adapted to receive a negative thereon, semi-cylindrical shutter means for said source comprising a stationary half portion and a swingable half portion complementary to said stationary portion, an electric circuit including a solenoid, time-controlled switch means for controlling operation of said solenoid, said swingable half portion having a reflecting inner

- surface, reflecting members at either side of said source, and means including gearing oscillatably operable by said solenoid and in engagement with said swingable portion for swinging the latter into open and closed positions, respectively, said swingable portion when swung in closed position surrounding with said stationary portion said light source, said swingable portion when swung in open position substantially overlying said stationary portion and permitting by its inner surface and in conjunction with said reflecting members transmission of said rays from said light source through said platen and said negative when located on the latter.
6. In a copying machine of the character described the combination of a short wave length light source, semi-cylindrical shutter means eccentrically arranged with respect to said source, an electric circuit, electro-magnetic means in said circuit, a hemi-cylindrical transparent platen fixedly positioned above said source and adapted to receive a negative thereon, reflecting means extending from adjacent said shutter means toward said platen and adapted to direct rays from said source against said platen time-controlled switch means in said circuit for controlling said electro-magnetic means, said shutter means comprising complementary members, a stationary member and a swingable member, respectively, and a curved filter element associated with said swingable member and encompassing therewith

said light source, said swingable member being in driving connection with said electro-magnetic means and having a reflecting inner surface, said swingable member when swung in a position above said source forming with said stationary member a substantially closed housing for said source, and when swung in a position below said source exposing said light source through said filter element and permitting direction of rays of light by said reflecting means and said inner surface to said platen and said negative when located on the latter.

7. In a copying machine of the character described the combination of a short wave length light source, a hemi-cylindrical transparent platen fixedly positioned above said source and adapted to receive a negative thereon, shutter means eccentrically arranged relatively to said source and comprising complementary shells, a stationary half shell and a movable half shell, respectively, means adapted to arrange said movable shell in one position diametrically to said stationary shell to conceal said light source, and means adapted to dispose said movable shell in another position substantially coincidently with said stationary shell to expose said light source permitting rays of light therefrom for transmission through said platen and said negative when located on the latter.
